UNITED STATES PATENT OFFICE.

ISAAC H. ATHEY, OF CHICAGO, ILLINOIS, ASSIGNOR TO DUST PROOF
FURNITURE COMPANY, A CORPORATION OF ILLINOIS.

FILE-CABINET.

No. 821,575.

Specification of Letters Patent.

Patented May 22, 1906.

Application filed June 19, 1905. Serial No. 266,038.

To all whom it may concern:

Be it known that I, ISAAC H. ATHEY, a citizen of the United States, residing at Chicago, in the county of Cook and State of Illinois, 5 have invented certain new and useful Improvements in File-Cabinets, of which the following is a specification.

My invention relates to file-cabinets, and has particular reference to extension-slides 10 for cabinet-drawers.

The general objects of the invention are to provide slide-bearings capable of supporting a drawer in a fully-extended position or substantially outside of the case or cabinet and 15 which will carry the drawer in such a manner as to eliminate binding or undue friction between the slides, drawer, or frame and to effect an arrangement which is light, strong, compact, and simple.

20 With the above objects in view my invention consists in the novel construction and combination of parts hereinafter described in detail, illustrated in the drawings, and incorporated in the claims.

25 In the drawings, Figure 1 is a perspective view of a cabinet case and drawer to which my invention has been applied. Fig. 2 is an enlarged vertical section through one side of the drawer and its extension-slides and bearings, taken substantially on line 2, 2, Fig. 5. Fig. 3 is an enlarged perspective view of one of the telescopic slides or sheet-metal bearing members which support the drawer. Fig. 4 is a transverse vertical section through case 30 and drawer. Fig. 5 is a longitudinal vertical section taken substantially on line 5, 5 of Fig. 4. Fig. 6 is a similar view showing the slides pulled out or fully extended. Fig. 7 is an enlarged perspective view showing a fragment of the ball-race portion of one of the slides.

Referring to the drawings, 2 represents the case, and 3 the drawer proper, which is mounted upon a series of telescoping or overlapping extension-slides 4, 5, 6, 4', 5', and 6'. Said slides are made of sheet metal stamped into a form which provides ball-races 7, 8, 9, 7', 8', and 9'. The slides are substantially alike, the only difference between them being 45 in the widths of their vertical sides 10, 10', and 10''. The members 7, 8, 8', and 9, 9' have horizontal flanges 11, 12, 13, 11', 12', and 13', respectively, which normally-overlie each other, but are held apart to prevent

friction between them, as will be more fully 55 explained hereinafter. The lower edge of each bearing member is stamped or bent into the form of a trough, channel, or ball-race 14, having sides 15 and 16, which are inclined toward the arched or laterally-curved bottom 60 17. The under side of the bottom 17 presents a concave ball-bearing surface, upon which the slide moves over the antifriction-balls 18 or bearing below, while the upper side of the bottom 17 presents a convex bearing-surface, upon which the superposed slide-bearing or its balls 18 moves or move. By this arrangement only the thickness of the metal is interposed between the series of balls. On each of the members 7, 8, 7', and 8' are inwardly-projecting beads or ridges 19 and 20, which serve as ball-retainers that 70 confine the balls or prevent them from escaping upwardly from the ball-race or channel 14. One end of the bottom 17 is extended 75 and the extended portion bent upwardly to provide a forward ball-stop 21, while the opposite end of said bottom is likewise extended, but bent downwardly to provide a rear stop 22, which serves to limit the outward 80 movement of each slide, as will appear hereinafter. A stop 23 is also shown, which serves in the same capacity as the stop 21—namely, to prevent the balls from rolling out at the ends of the ball-race 14. The upper 85 bearing members 9 and 9' are attached to the usual drawer-rails 24, 24'. As slide-bearings 9 and 9' do not support any balls on their convex sides, but simply rest upon the balls or utilize their convex surfaces as bearings, 90 the ribs 19 and 20 are omitted from said bearings; otherwise they are no different from bearings 7, 7', and 8, 8'.

The entire series of bearings, comprising 95 7, 7', 8, 8', 9, and 9', are carried upon stationary sheet-metal ball-races or slide-supports 25, 25', which rest on the usual side rails 26, 26', secured to each inner wall of the ball-race portions of slides 7, 7', 8, 8', 9, and 9', or the ball-race 14, (shown in Fig. 3,) comprising 100 walls 15 and 16, beads or ribs 19 and 20, and curved bottom 17.

Ordinarily only two balls are necessary for each bearing, and I prefer to employ that number. As shown in the several views, the two balls are spaced apart by means of spacers 27, which may be employed in shorter lengths where more than two balls

are used. After the initial opening and closing movements of the slides the antifriction-balls will of course remain the proper relative distances apart regardless of the spacers. 5 I do not, however, wish to be confined to this particular method of spacing the balls apart, as I may prefer to employ other devices for that purpose.

It will be seen by reference to Fig. 7 that 10 the peculiar construction of the ball-race 14 provides two bearing-points for the balls—namely, at 28 on the side 15 or at 28' on the opposite side and at the apex 29 of the convex side of bottom 17. The diameter of each 15 ball 18 is in the plane of the horizontal axes of the balls a little less than the width between the sides or walls 15 and 16 of the ball-races, this in order to prevent said balls from touching both sides at once. Two ball 20 tracks or rails, as it were, are thus provided in the ball-race—namely, along the apex of the convex side of bottom 17 and along a line touching one of the sides of the ball-race, while the under or concave side of the ball- 25 race bottom 17 immediately above forms the upper or third bearing-point, making a three-point bearing for each ball 18.

The vertical sides 10, 10', and 10'' of the extension-slides are spaced apart slightly or 30 sufficiently to keep them from rubbing against each other when the balls are supported on the two lower bearing-points or ball-tracks referred to as comprising bearing-points 28 and 29 or 28' and 29', which bearing-points serve also as lateral thrust-bearings supporting the weight of the drawer and slides laterally as well as in a vertical direction, thus confining the friction to that which takes place between said sides near the horizontal flanges 11, 11', 12, 12', 13, and 13'. 35 The latter need not touch each other at all, nor need they touch the side of the case 2 when the parts are accurately adjusted. A side rail 26'' is secured to each inner vertical 40 wall of the case immediately above said horizontal flanges, between which and the lower rails or slide-bearings 26 and 26' the two sets of extension-slides are held against tilting, while serving as tracks for the moving slides. 45

50 In order to obtain free and easy movement of the extension-slides, it is necessary that there should be no binding or bending strain between said slides while they move and that the slide or slides shall during their movement along their bearings rest with their whole weight or weights upon said bearings until they reach the ends of their respective paths and in turn become stationary tracks or slide-supports. For the purpose of 55 giving such support to the moving slides and to cause them to rest entirely upon the balls underneath the slide I limit the outward movement of each slide to less than one-half its length. This prevents it from progressing 60 to a point where its center of gravity is

carried beyond the end of the stationary slide or slide-bearing. I also arrange the slides to move in consecutive order, the slide last to move serving as stationary bearing for the slide whose next turn it is to 70 move. Then the latter slide takes up the extension movement and comes to a standstill just before it reaches the overbalancing point, or where the center of gravity would be carried beyond the foremost ball. In 75 Figs. 1 and 2 the arrangement for effecting this consecutive movement is clearly shown. A description of the operation of slides 4, 5, and 6 will serve for both sides or series of slides. The slide 6 on one side of the drawer 80 is provided with a stud, projection, or pin 30, which when all of the slides are telescoped or overlap each other in the closed position of the drawer occupies apertures 31 and 32 in slides 5 and 4, respectively, the slide 4 being 85 the outside slide. When said slide, together with slides 5 and 6, have been drawn forward until the stop 22 on slide 4 reaches the end of the path of spacer 27, the drawer or slides 5 and 6 cannot move farther unless the pin or 90 stud 30 is released from one of the slides. The engagement of pin 30 with aperture 32 or slide 4 being the point of least resistance, (the slide 5 being outside of slide 6,) the pin or stud 30 will slip out of the aperture 32 and 95 permit slides 5 and 6 to move together as a unit until the stop 22 on slide 5 has reached the end of its path; when the pin 30 must yield its engagement of the aperture 31 and permit slide 6 to move upon the slide 5. As 100 shown in Fig. 6, less than one-half the length of each slide is drawn over the slide or bearing underneath, the slide 4 being stopped before its overweight is beyond the end of its bearing 25. Then bearing or ball-race 7 becomes 105 stationary and 5 and 6 move together thereon until slide 5 has been arrested in its outward movement by its stop 22, when slide 6 will move on the now stationary bearing 8 to the end of its path, or before its center of 110 gravity has passed the end of slide 5. In this manner any number of slides can be employed and the extension carried on indefinitely, the moving slide or slides always traveling, as it were, upon its or their own wheels 115 and resting firmly upon the stationary track. When the return movement takes place, the same action will control, because the outer ends of slides 4 and 5 being overweighted by 120 slides 6 6' and drawer 3 the flanges 11 and 12 will obviously be caused to bind against each other and hold slides 4 and 5 stationary, while slide 13, which is not overbalanced on bearing 8, will move easily until it shall have telescoped the slide 5 and have carried the 125 overweight of slide 6 and 5 within the end of slide 4. Slides 5 and 6 will then be released from binding between flanges 11 and 12 and 130 be free to move over slide 4 on its bearing 7 until the center of gravity has been carried

within the end of case or cabinet 2, so that the weight of all the slides will rest on bearing 25.

Having described my invention, I claim as new and desire to secure by Letters Patent—

1. The combination with a file-cabinet, or the like, and a drawer, or the like, of a series of telescoping extension-slides, ball-bearings for said slides, and means for supporting said slides upon each other so that the ball-bearing portions thereof will be held apart to prevent frictional slide contact.

2. The combination, with a cabinet case and drawer, of a plurality of telescopic slides, ball-bearings for said slides, said bearings being constructed to provide three-point bearings for said balls.

3. In combination, slide-supports, a plurality of extension-slides mounted on said slide-supports to move thereupon and upon each other, the intermediate of said extension-slides having sheet-metal bearings or ball-races provided with bottoms which

serve as movable slide-bearings for the respective slides and as stationary ball-races 25 for superposed extension-slides.

4. The combination, with a drawer or the like, of slide-supports, a plurality of slides all normally overlying said slide-supports and drawer, but extensible to support said drawer 30 beyond the ends of said slide-supports, means for limiting the outward movement of each slide, and means for interlocking said slides so that they will move together as a unit, said means permitting release of each slide 35 from interlocking engagement with its companion slide or slides when it reaches the end of its outward path of movement.

In testimony whereof I have hereunto set my hand in the presence of two subscribing 40 witnesses.

ISAAC H. ATHEY.
